UNITED STATES PATENT OFFICE.

EVERETT H. BARNEY, OF SPRINGFIELD, MASSACHUSETTS.

SKATE-FASTENING.

SPECIFICATION forming part of Letters Patent No. 248,273, dated October 18, 1881.

Application filed March 25, 1881. (Model.)

To all whom it may concern:

Be it known that I, EVERETT H. BARNEY, a citizen of the United States, residing at Springfield, in the county of Hampden and State of Massachusetts, have invented new and useful Improvements in Skate-Fastenings, of which the following is a specification.

This invention relates to the details of the construction of devices for forcing the sole and heel clamps of a skate against the sole and heel of a boot to fasten the skate to the latter; the object being to provide improved devices for operating the sole-clamps of a skate transversely under the sole-plate and the heel-clamp longitudinally under the heel-plate from one source of power, and such devices as permit of conveniently adjusting said clamps to different sizes of boots, and such as can be wholly operated without keys or implements other than the parts proper of the fastenings themselves, and can be almost instantaneously detached from the skate.

In the drawings forming part of this specification, Figure 1 is a plan view of the bottom 25 of the skate embodying my improvements, in which the runner in the rear of the sole-plate is broken away, and in which the heel portion of the skate is shown partly in section. Fig. 2 is a side elevation of the same. Fig. 3 is a 30 view of the skate-fastening devices detached from the skate. Fig. 4 is a view of the screwed clamp-rod detached from the other parts of the skate-fastenings.

In the drawings, *a* is the sole-plate. *e* is the 35 runner. *c* are the sole-clamps. *i* is a sole-clamp pivot and nut. *h* is a clamp-rod. *n* is the heel-plate. *o* is the heel-clamp. *v* is a turning-lever, pivoted on rod *h*.

The construction of the sole-plate and sole-clamps, and the means for securing the latter under the sole-plate *a* by studs having elongated heads, as shown herein, are substantially the same as those shown and described in my patent of May 2, 1876, to which reference may be had, and the construction of the heel-plate-supporting brackets shown herein, whereby they spread under said heel-plate and have a longitudinal chamber for the reception of the hollow shank of the heel-clamp, is also substantially like that shown in my patent of February 20, 1877, and the heel-clamp *o* and

the clamp-rod *h*, shown herein, are constructed and operated much like those shown in the last-named patent, the difference being that the cam-lever there shown is herein replaced by the turning-lever *v*. The ends of the sole-clamps *c*, which meet in the rear of the sole-plate, are so formed as to overlap each other, and are perforated to receive the pivot-nut *i*, upon which they swing as the clamp-jaws move to and from the edge of the sole-plate. The said pivot-nut *i* is perforated transversely and tapped to receive the screwed end of the clamp-rod *h*, as shown herein. The turning-lever *v* is pivoted to one end of said clamp-rod, as shown, and serves as an abutment against which the heel-clamp bears as said rod is screwed into the pivot-nut *i* to force the clamps against the boot, and its form allows of its being turned up, as in Fig. 2, out of the way after the skate is fastened on, and the strain upon it occasioned by screwing up rod *h* keeps it in an upright position while the skate is being worn.

If desired, the clamp-rod *h* may be made as shown in Fig. 4, in which case the turning-lever *v* may be dispensed with and said rod be operated by a hollow key fitting the squared end of said rod, Fig. 4.

The operation of my improved skate-fastening devices is as follows: The turning-lever *v* is turned down to the position shown in Fig. 3, and by turning it the clamp-rod *h* is unscrewed from the nut *i* until the jaws of the sole-clamps and the heel-clamp are free to be moved sufficiently far from the edges of the sole-plate and from the rear of the heel-plate to permit of placing a boot thereupon between said clamp-jaws, when said clamp-rod *h* is, by the aid of said turning-lever, screwed back into the pivot-nut *i* until said pivot-nut *i* is drawn back toward the heel-plate, drawing with it the clamps under the sole-plate, causing them to slide on the studs *x* thereon and their upright jaws to be forced against the boot-sole, when the rod *h* will be drawn forward, forcing the heel-clamp strongly against the rear of the heel and forcibly locking all of the clamps against the boot. The lever *v* may now be turned up out of the way, as in Fig. 2. The skate is removed from the boot by unscrewing rod *h*, whereby said clamps are again freed. To detach the sole and heel-clamps from the

- skate the rod *h* is unscrewed quite out from the pivot-nut *i*, when said rod and the heel-clamp may be drawn out from under the heel-plate, and by removing the pivot-nut, which is now free, from the ends of the sole-clamps, the ends of the latter may be swung apart until the long heads of the studs *x* in the sole-plate will pass through the slots in the clamps *c*, when the latter may be freely removed from said sole-plate.
- 10 The great advantages of the construction herein described over others in which similar sole and heel clamps have been employed consist in the simple and effective means provided for operating all of said clamps through the 15 single element, the rod *h*, which may be turned with any suitable key. This is made practicable by uniting the rear ends of the sole-clamps *c c* upon the nut *i*, upon which said clamps pivot, and so arranging said nut that 20 it is forced to move rearwardly upon rod *h* as the latter is turned with sufficient power to carry the jaws of the sole-clamps effectively against the boot-sole. The said sole-clamps, in

combination with the nut *i* and rod *h*, when the latter is allowed to pass from the rear end 25 of the skate under the heel-plate, and be stopped in its forward movement by a collar fixed upon it, as in Fig. 4, which abuts against the rear part of the skate, constitute a most effective and simple fastening device for the sole-plate, 30 and said parts may be so used without the heel-clamp herein shown.

I do not claim a threaded rod carrying a nut arranged to operate two pivoted clamps; but

I claim—

35 The combination of the longitudinal clamp-rod *h*, sole-clamps *c c*, sliding and vibrating on the pins *x*, and nut *i*, constituting the pivot of both clamps, connecting the latter and adapted to the threaded end of the rod *h*, substantially 40 as set forth.

EVERETT H. BARNEY.
